CASING FOR A HAIR DRYER

Walter E. Moore, St. Louis, Mo., assignor to Knapp-Monarch Company, St. Louis, Mo., a corporation of Delaware

Filed Dec. 27, 1960, Ser. No. 63,345

Term of patent 14 years

(Cl. D86—10)

I claim:

The ornamental design for a casing for a hair dryer, substantially as shown.
